UNITED STATES PATENT OFFICE

115,983

DESIGN FOR A JACKET

Perkins H. Bailey, New York, N. Y., assignor to Talon, Inc., Meadville, Pa., a corporation of Pennsylvania

Application May 20, 1938, Serial No. 77,310

Term of patent 14 years

To all whom it may concern:

Be it known that I, Perkins H. Bailey, a citizen of the United States, residing at New York, in the county of New York and State of New York, have invented a new, original and ornamental Design for a Jacket, of which the following is a specification, reference being had to the accompanying drawing, forming a part thereof.

In the drawing:

The figure shows the front view of a jacket showing my design.

The back of the jacket is conventional.

I claim:

The ornamental design for a jacket, substantially as shown and described.

PERKINS H. BAILEY.
